UNITED STATES PATENT OFFICE.

JAMES H. GRAHAM, OF TORRINGTON, CONNECTICUT, ASSIGNOR, BY MESNE ASSIGNMENTS, TO THE TORRINGTON COMPANY, OF TORRINGTON, CONNECTICUT, A CORPORATION OF CONNECTICUT.

SUCTION CARPET-CLEANER.

1,384,998.

Specification of Letters Patent. Patented July 19, 1921.

Application filed August 16, 1917. Serial No. 186,551.

To all whom it may concern:

Be it known that I, JAMES H. GRAHAM, a citizen of the United States, residing at Torrington, in the county of Litchfield, State 5 of Connecticut, have invented certain new and useful Improvements in Suction Carpet Cleaners, of which the following is a description, reference being had to the accompanying drawing and to the figures of 10 reference marked thereon.

My invention relates to improvements in suction carpet cleaners.

An object of the invention is to provide a suction sweeper in which the bellows are 15 vertically disposed so as to take up less space and allow the operating pitmen therefor to be connected directly thereto and also allowing of the shortening of the dust chamber and also the widening of the same 20 in a housing of the usual height but of less length.

Another object of the invention is to provide a sweeper in which the suction nozzle is pivotally mounted and carries a vertically 25 adjustable brush, said brush being adjusted from a single point and also providing means whereby a constant pressure is obtained between the drive wheels and the friction rollers on the brush when the brush 30 is in its raised or lowered position.

A still further object of my invention is to provide a sweeper which is simple in operation and construction and having certain details and combination of parts to accomplish the above objects, as will be hereinafter more fully described.

In the accompanying drawings:—

Figure 1 is a perspective view of the forward end of a sweeper showing the nozzle 40 locking means and brush adjusting means.

Fig. 2 is a vertical longitudinal sectional view of my sweeper showing the nozzle in its elevated position.

Fig. 3 is an enlarged side elevation of 45 the forward end of the sweeper.

Fig. 4 is a top plan view showing the rear portion of the housing broken away to show the arrangement of the bellows and the crank and pitman connections for operating 50 the same.

Fig. 5 is an enlarged perspective view of one end of the brush spindle showing the manner of mounting and adjusting the same the bristles not being shown.

Fig. 6 is a side elevation similar to Fig. 55 3 showing a portion of the forward friction wheel broken away to show the manner of supporting it so that it will have an even tension on the friction roller of the rotary brush.

Fig. 7 is a bottom perspective view of the forward end of the sweeper to show the spring yoke for supporting the forward supporting wheels.

Fig. 8 is an enlarged perspective view of 65 the bellows, crank and connections in their disassembled relation.

Fig. 9 is an enlarged perspective of the nozzle locking means and the wheel supporting means in their disassembled relation. 70

Fig. 10 is an enlarged diagrammatical view of the drive wheel and friction roller of the brush showing their relations when in the several adjusted positions.

Fig. 11 is a transverse sectional view of 75 the buffer carried by the front of the sweeper, and

Fig. 12 is a perspective view of the buffer showing the several parts in their disassembled relation.

Referring now to the drawings, 1 represents the housing which is of the usual material and provided with the usual handle by means of which the sweeper can be pushed over the surface to be swept. The rear end 85 of the housing has mounted therein a shaft 3, said shaft being rotatably journaled in bearings 4 and 5 carried by the sides 6 and 7 of the housing and has rigidly secured thereon on the inside of the sides of the 90 housing the supporting wheels 8 and 9. The said shaft intermediate the wheels is provided with a series of cranks 10 which, as shown, are three in number to correspond with the number of bellows 11. The bellows, as shown, are vertically disposed in the housing having their small ends down.

Connected to the movable side walls 12 of the bellows are plates 13 provided with ears 14 having rolled outer ends forming bearings for the pins 15 which connect the pitmen 16 to the bellows. The outer ends of the pitmen are split as indicated at 17, having semi-circular grooves 18 forming bearings for the cranks 10 and said split portions are held around the cranks by means of the bolts 20.

The upper ends of the stationary walls 21

of the bellows are provided with openings 22 closed by the flap valves 23 communicating with the dust chamber 24 which is practically of square form and has an opening 24' at the front which communicates with the front end of the main housing. Within the dust chamber is arranged the dust bag 26 which is well understood and needs no detail description.

10 The sides 6 and 7 of the housing at the front end have secured thereto the plates 27 and 28 which have at their upper ends the outwardly extending arms 28' which extend some distance beyond the housing and are provided with horizontally arranged slots 29. The vacuum or suction nozzle 30 is of a width equal to the housing and completely covers the front end of the housing. The upper end of the nozzle is provided with plates 31 and 31' having outwardly extending pins 32 passing through the slots 29 in the plates 27 and 28 whereby the nozzle is pivotally supported by the housing so that it can be swung upwardly away from the end of the housing so that the dust bag can be removed as shown in Fig. 2 of the drawings.

Each of the plates 27 and 28 has a lever 33 pivoted thereto and connected to each lever is a hook 34 the outer ends of which hook over studs 35 carried by U-shaped plates 36 on the nozzle for drawing it tightly against the outer end of the housing to form a tight joint therewith as shown in Fig. 7 of the drawings. The hooks are so arranged as shown, that the lever passes a center line between its pivot and the stud 35 and thereby the lever cannot be moved by pressure on the nozzle.

40 The nozzle, as shown, has a slot 37, entirely across its upper end communicating with the dust chamber and also has a slot 38 in its lower face which is surrounded by a rubber or other packing 38' to form a tight fit with the surface being swept and also to prevent the nozzle from injuring the floor. Within the nozzle is an elongated rotary brush 39 which has its trunnions 40 extending out through vertical slots 41 in the ends 45 of the nozzle and whereby said brush may be moved vertically. Extending across the front of the nozzle is a yoke 42 which has its ends extending around the ends of the nozzle and spaced some distance therefrom. 50 Rigidly secured to the inner face of the yoke are the plates 43 and 44 which likewise extend around the ends of the nozzles and are spaced from the ends of the yoke. The trunnions 40 of the brush 39 extend through both the plates and ends of the yoke and are mounted on the trunnions between the same are friction rollers 45 and 46 by means of which the brush is rotated as will be later described. The ends of the yoke have bolts 55 or screws 47 loosely passing therethrough

and rigidly secured in the ends of the nozzle and housing and constitute pivots for the yoke whereby it can be rocked for raising and lowering the brush. One end of the nozzle has a plate 48 secured thereto, provided with a rigid outwardly extending screw threaded stud 49 which passes through an elongated slot 50 in the link 51. The link 51 is adjustably held on the stud by the thumb nut 52 and the lower end of the link 70 is connected to the plate 43 on the outside of the pivot 47 so that the raising and lowering of the link rocks the yoke and raises or lowers the brush. By this structure it will be seen that the brush is raised by a single 75 means thus insuring an equal raising or lowering of both ends of the brush so as to give an even pressure of the brush throughout its length on the surface being swept.

The plates 27 and 28 have headed studs 53 80 extending through openings in their front edges and secured to the housing and upon which are pivotally mounted the plates 54. The said plates, below their pivoted connection with the housing, are provided with 85 stub axles 55 upon which are mounted the forward anti-friction and brush driving wheels 56 and 57. The lower ends of the plates 54 are provided with slots 57' through 90 which extend the lugs 58 carried by the plates 27 and 28 which hold the plates 54 against lateral movement and also limit the 95 swinging movement of the plates. Connecting the lower ends of the two plates 54 is a wire loop 59 which extends entirely across the housing below the bottom and is secured thereto by means of the clip 60 as shown in Fig. 7 of the drawings. It will be seen that by the resiliency of the loop 59 the forward 100 drive wheels will at all times have an even pressure on the friction rollers carried by the rotary brush in the nozzle.

105 The yoke 42 at the proper intervals is provided with slots 61 and covering said yoke is a strip of felt or rubber 62 forming 110 a buffer and said felt or rubber is held on the yoke by U-shaped clips 63 passing through the slots and having their ends passing through the slots 61 and turned in opposite directions on the inside of the yoke 115 as indicated at 64, Fig. 11. The clips 63 will embed themselves in the felt or rubber so that they will not mar or scratch.

120 The operation of the sweeper is as follows: The housing is rolled on the floor by the handle in the usual manner which rotates the rear supporting wheels 8 and 9 which operate the shaft 3 and through the medium of the pitmen the bellows are operated to cause a suction or vacuum in the chamber 24 for drawing the dust through the nozzle. The forward wheels 56 and 57 are likewise rotated by friction with the floor and engage the friction rollers 45 and 46 and rotate the brush. These wheels being sup- 125 130

- ported by the yoke 59 through the medium of the pivoted plates 54 it will be seen that the more pressure is applied to the handle in a downward direction the greater will be the pressure of the wheels 56 and 57 on the friction rollers 45 and 46 to cause a positive drive of the rotating brush. When it is desired to cause a greater or less pressure of the brush on the floor, the thumb nut 52 is loosened and the link 51 raised or lowered which rocks the yoke 42 on the pivots 47 and the brush being carried by the ends of the yoke beyond the pivot, is then raised or lowered and when properly adjusted, the thumb nut is tightened, holding the links and locking the brush in its adjusted position. When it is desired to remove the dust the levers 33 are drawn upwardly until the pivotal connection between them and the levers is above the pivot of the levers when the hooked ends may be thrown upwardly from over the studs 35 and the nozzle is then free to swing upward upon the studs 32 into the position shown in Fig. 2 of the drawings.
- Having thus described my invention, what I claim as new and desire to secure by Letters Patent, is:—
1. A carpet sweeper comprising a housing, side plates attached to said housing, a brush carrying nozzle pivoted to one of said plates, a lever pivoted to said plates, a second hooked lever pivoted to said lever, a stud carried by said nozzle and engageable by said hooked lever to hold the nozzle tightly against the housing.
  2. A carpet sweeper comprising a housing including a vacuum means, a nozzle connected to said housing and communicating with said vacuum means, a brush rotatable in said nozzle and having friction wheels, plates pivotally mounted on said housing, said plates provided with trunnions, friction wheels mounted on said trunnions engaging said first-mentioned wheels, and a spring yoke carried by said plates and connected to said housing whereby to permit the engaging pressure between said friction wheels to vary.
  3. A carpet sweeper, comprising a housing, a vacuum means therein, a nozzle carried by the housing and in communication with the vacuum means, a rotary brush adjustable in the nozzle, means for adjusting said brush, friction rollers carried by the brush, pivoted plates carried by the housing, wheels carried by the plates and engaging the friction rollers carried by the brush, and a spring yoke connecting the lower ends of the pivoted plates whereby the pressure of the wheels on the rollers is varied.
  4. A carpet sweeper comprising a housing, a vacuum means therein, a nozzle carried by the housing, a rotary brush in the nozzle, friction rollers carried by the brush, pivoted plates carried by the housing, wheels carried by the plates and engaging the friction rollers carried by the brush, and a spring metal yoke carried by the housing and connecting the lower ends of the pivoted plates whereby the pressure of the wheels on the rollers is varied with the pressure applied to the sweeper.
  5. A carpet sweeper comprising a housing, a vacuum means therein, a nozzle carried by the housing, a rotary brush vertically movable in the nozzle and having its trunnions extending beyond the ends of the nozzle, a yoke pivoted to the nozzle and having bifurcated free ends in which the trunnions of the brush are journaled, friction rollers rigidly secured to the trunnions in the bifurcated ends of the yoke, a link connected to the yoke, means for adjustably securing the link to the nozzle whereby the brush is held in its adjusted position and wheels carried by the housing and engaging the friction rollers carried by the brush.
  6. A carpet sweeper comprising a housing, a vacuum means therein, a nozzle carried by the housing and in communication with the vacuum means, a rotary brush in the nozzle and vertically movable therein and having its trunnions extending beyond the ends of the nozzle, a yoke pivoted to the nozzle and having bifurcated free ends in which the trunnions are journaled, friction rollers rigidly carried by the trunnions in the bifurcated ends of the yoke, a link connected to the yoke, means for adjustably securing the upper end of the link to the nozzle for vertically adjusting the brush, plates pivoted to the sides of the housing, stub axles carried by the plates, wheels mounted on said stub axles and engaging the friction rollers on the brush, and a spring metal yoke connecting the lower ends of the plates and connected to the housing whereby the pressure of the wheels on the rollers is varied with the downward pressure applied to the sweeper.
- In testimony whereof I affix my signature in the presence of two witnesses.
- JAMES H. GRAHAM.
